LOOP-TAKER MOUNTING MEANS FOR
SEWING MACHINESEdward M. Hanf, Bridgeport, Conn., assignor to
The Singer Manufacturing Company, Eliza-
beth, N. J., a corporation of New Jersey

Application January 2, 1951, Serial No. 204,046

6 Claims. (Cl. 112—196)

1

This invention relates to sewing machines and more particularly to a loop-taker housing and means for removably securing the housing to a sewing machine frame.

The present invention is particularly adapted for use with a two-thread lock-stitch sewing machine of the type employing either a rotary or an oscillating shuttle which is journaled within a housing which is adapted to be detachably mounted upon the sewing machine frame.

It is a primary object of this invention to provide a loop-taker housing unit which may be readily and inexpensively attached to a sewing machine and which may with facility be replaced in the field by a new similar housing unit in the event that the original unit becomes damaged by accident or wear.

To the attainment of the ends in view, the invention comprises the devices, combinations and arrangements of parts hereinafter described and more particularly pointed out in the claims.

The features of the invention and the advantages attained thereby will be readily understood by those skilled in the art from the following detailed description of a preferred embodiment of the invention illustrated in the accompanying drawings in which:

Fig. 1 represents a front face view of a loop-taker housing in which the present invention is incorporated, and as embodied in a sewing machine shown partly in section.

Fig. 2 represents a perspective view, partly in section, of the sewing machine bed casting which carries the loop-taker housing.

Fig. 3 represents a perspective view of the inner face portion of the loop-taker housing with an oscillatory shuttle element mounted within such housing.

Fig. 4 represents a fragmentary sectional view taken substantially along the line 4—4 of Fig. 1.

Fig. 5 represents a sectional view taken substantially along the line 5—5 of Fig. 4.

Fig. 6 represents a perspective view of one of a pair of dowel pins employed in the present loop-taker housing.

The sewing machine bed casting 10 is formed with a central supporting leg 11, of which the sides are widened at 12, 12 and faced to form arcuate or segmental seats 13, 13 to which is secured by screws 14, 14 a loop-taker housing of a type which is broadly disclosed in the E. B. Allen Patent No. 1,869,402, August 2, 1932.

Broadly, the present loop-taker housing comprises a pair of arcuate members 15 and 16 which are secured together by means of a pair of screws

2

17, 17 passing through aligned apertures in the members 15 and 16. The exposed surface 18 of the member 16 is complementary to the surfaces 13, 13 and whenever the loop-taker housing is secured to the sewing machine frame 10, the surface 18 is disposed in abutting relation with the complementary surfaces 13, 13. These surfaces 13, 13 and 18 are normally ground so as accurately to position the loop-taker housing in proper alignment with the cooperating actuating elements of the sewing machine.

The inner cylindrical surface of the housing member 16 is cylinder ground, as at 19, to form a supporting bearing or raceway for the circular bearing rib 20 of the usual oscillatory shuttle 21 having a loop-seizing beak 22, a throat 23 and a heel 24, which throat and heel portions are engaged by the arms 25 and 26 of the usual oscillatory shuttle driver 27 carried by the shuttle-driving shaft 28 journaled at one end in the leg 11. Whenever the loop-taker housing with its shuttle 21 is mounted in its operative position, as illustrated in Fig. 1, the shuttle driver 27 functions to actuate the shuttle 21 in the usual manner, and since this shuttle-driving mechanism is old and does not come within the purview of the present invention, no further detailed description thereof will be presented herein.

As pointed out hereinabove, the present loop-taker housing is adapted to be secured to the sewing machine frame by means of a pair of screws 14, 14. The shank portion of each of these screws is adapted to be loosely located within a respective one of the aligned apertures 29 formed within the housing elements 16 and 15, while the threaded end portion of each screw is threadedly received within a respective one of a pair of apertures 30 provided in the surfaces 13, 13 of the frame member. This construction permits the loop-taker housing to be readily applied to and removed from a sewing machine frame but, of course, means must be provided for accurately locating the loop-taker housing relative to the shuttle driver 27, as well as to the reciprocating needle 31. To this end, the present invention contemplates the provision of a pair of dowel pins, of which each is designated by the numeral 32. Each of these dowel pins includes a cylindrical shank portion 33 as well as an enlarged head portion 34. As may be best understood by reference to Figs. 3, 4 and 5, each of the dowel pins 32 has its shank portion 33 loosely received within an aperture 35 formed within the loop-taker housing element 16, while the enlarged head portion 34 of the dowel pin is loosely received within a cham-

ber or counterbore 36 which communicates directly with the aperture 35. From this it will be appreciated that the dowel pins are circumferentially spaced about the surface 18 and that they are laterally adjustable relative to such surface.

Cooperating with the dowel pins 32, 32 are a pair of set screws 37, 37 of which each is threaded directly within the loop-taker housing member 15 so as to impinge upon a respective one of the head portions 34 of the dowel pins thereby to lock the dowel pin in a selective position of lateral adjustment.

In utilizing the present invention, the machine frame 16 is first provided with a pair of dowel-pin receiving holes 38, 38, of which each is disposed within a flat surface 13 and is dimensioned so as snugly to receive the shank portion 33 of one of the dowel pins. Thereafter, the loop-taker housing, with its set screws 37, 37 loosely positioned therein, is mounted in its customary location with the surface 18 abutting the surfaces 13, 13. The housing is then adjusted so as to cooperate properly with the shuttle 21 and the needle 34. Thereafter, the fastening screws 14, 14 are tightened with the frame holes 38, 38 so as to lock the housing in a fixed position. With the housing in this position, and with the dowel pins received within the holes 38, 38 of the sewing machine frame, the set screws 37, 37 are tightened against each of the dowel pins so as to fix them in a given position within the housing proper. Thereafter, if it becomes necessary to remove the housing, it may with accuracy be replaced upon its seats 13, 13 on the machine frame due to the fact that the dowel pins will function to relocate the housing in its initial position.

Furthermore, it will be appreciated that in the event that the original loop-taker housing becomes damaged, either by accident or through wear, and it has to be replaced in the field by a new housing, the present invention permits the old housing to be replaced with facility due to the fact that a new housing with its laterally adjustable dowel pins may be readily applied to the sewing machine irrespective of the fact that the new housing was not manufactured solely for placement upon said sewing machine. Thus, those skilled in the art will understand that the present loop-taker housing may be initially applied to a sewing machine with great facility and at a low cost and, furthermore, that it is also adapted to be applied as a replacement unit to a sewing machine in the field in the event that the original housing has become damaged. Also, it is to be understood that the present construction which includes the laterally adjustable dowel pins and their associated set screws are most efficient in use and at the same time are adapted to be inexpensively manufactured.

Having thus set forth the nature of the invention, what I claim herein is:

1. A loop-taker housing for removable attachment to a sewing machine, comprising, a loop-taker support having an aperture therein, a dowel pin located within said loop-taker support aperture and having its shank diameter substantially less than the maximum width of said aperture so as to be laterally adjustable therewithin, said dowel pin being longer than its associated aperture so as to project outwardly from said loop-taker support, and means carried by said loop-taker support for locking said dowel pin in a selective position of lateral adjustment within its associated aperture.

2. A loop-taker housing for removable attachment to a sewing machine having a pair of dowel-pin receiving apertures, comprising, an annular loop-taker support having a pair of circumferentially spaced apertures therein, a pair of dowel pins each located within a respective one of said apertures and having its shank diameter substantially less than the maximum width of its associated aperture so as to be laterally adjustable therewithin, each of said dowel pins being longer than its associated aperture so as to project outwardly from said loop-taker support, and means carried by said loop-taker support for locking each of said dowel pins in a selective position of lateral adjustment within its associated loop-taker support aperture.

3. A loop-taker housing for removable attachment to a sewing machine having a dowel-pin receiving aperture, comprising, a loop-taker support having an aperture therein, a dowel pin formed with a cylindrical shank and an enlarged head portion, said dowel pin having its shank located within said loop-taker support aperture and having its shank diameter substantially less than the maximum width of said aperture so as to be laterally adjustable therewithin and having its shank formed longer than its associated aperture so as to project outwardly from said loop-taker support, and means including a set screw threaded within said loop-taker support for engagement with the head of said dowel pin thereby to lock said dowel pin in a selective position of lateral adjustment within its associated aperture.

4. A loop-taker housing for removable attachment to a sewing machine having a pair of dowel-pin receiving apertures, comprising, a loop-taker support including two annular members secured together along a pair of abutting flat surfaces, one of said members being formed with a pair of circumferentially spaced apertures each leading from said abutting flat surfaces to the outside of said support, a pair of dowel pins each located within a respective one of said support apertures and having its shank diameter substantially less than the maximum width of its associated aperture so as to be laterally adjustable therewithin, each of said dowel pins being longer than its associated aperture so as to project outwardly from said support, and means carried by the other supported member for locking each of said dowel pins in a selective position of lateral adjustment within its associated support aperture.

5. A loop-taker housing for removable attachment to a sewing machine having a pair of dowel-pin receiving apertures, comprising, a loop-taker support including two annular members secured together along a pair of abutting flat surfaces, one of said members being formed with a pair of circumferentially spaced apertures leading to the outside of said support and a pair of counterbores each leading from a respective one of said support apertures to the abutting flat surfaces, a pair of dowel pins each formed with a cylindrical shank and an enlarged head portion and each being disposed with its shank and head portions positioned respectively within one of said support apertures and one of said counterbores with the diameter of said shank and the diameter of said head each being substantially less than the maximum width of its associated aperture or counterbore so as to be laterally adjustable therewithin, each of said dowel pins having its shank formed longer than its associated support aperture so as to project outwardly from said support, and a pair of set screws each threaded

within the other of said support members for engagement with the head of a respective one of said dowel pins thereby to lock said dowel pin in a selective position of lateral adjustment within its associated aperture.

6. A sewing machine comprising, in combination, a frame having a flat surface formed with a pair of spaced apertures therein, a loop-taker support having a flat surface complementary to said frame surface for removable attachment in abutting relation therewith, said support surface being formed with a pair of spaced apertures complementary to said first mentioned apertures with respect to location but different with respect to their lateral dimensions, a pair of dowel pins each located within a respective one of the larger pair of said apertures with the shank diameter of each pin being substantially less than the max-

imum width of its associated larger aperture so as to be laterally adjustable therewithin, each of said dowel pins being longer than its associated larger aperture and having its shank diameter substantially equal to the width of a respective one of said smaller apertures so as to fit snugly therewithin, and means associated with said loop-taker support for locking each of said dowel pins in a selective position of lateral adjustment within its associated larger aperture.
